UNITED STATES PATENT OFFICE.

FREDK. E. SICKELS, OF NEW YORK, N. Y.

METHOD OF CONTROLLING MOTIVE POWER.

Specification of Letters Patent No. 5,765, dated September 12, 1848.

To all whom it may concern:

Be it known that I, FREDERICK ELSWORTH SICKELS, of the city, county, and State of New York, have invented a new and improved mode of applying and controlling a propelling force at the will of the operator for the purpose of causing any driving machinery to which this propelling force is applied to move only with a corresponding motion to the motion of the operator with more accuracy and efficiency than has been done by any means heretofore known.

By a motion of the operator I mean a motion of the whole or any part of the body of the operator that is attached to, and acts on and in combination with a regulating connection hereafter described, to produce a corresponding motion of the driving machinery. By a corresponding motion of the driving machinery I mean a motion of the driving machinery, corresponding relatively, in time, duration, velocity and direction, to the motion of the operator. By the driving machinery I mean the machinery to which the propelling force is applied, and which machinery moves only in connection with the regulating connection. By the applying machinery I mean the machinery which is moved by the regulating connection to regulate the amount and apply the propelling force.

The nature and character of my invention and that which distinguishes it from all other things before known or used, consists, in making a connection from the applying machinery to the driving machinery which is acted on by an operator in such manner as that by the motion of the operator, this regulating connection will act on the applying machinery, and thereby regulate the amount of propelling force applied.

In Figure 1 of the accompanying drawings this regulating connection is shown attached to the machinery, operating a "D slide valve" as the applying machinery, and to the machinery connected with the piston of a cylinder as the driving machinery, and to a handle for the operator; the propelling force being, air, gas, steam, or fluid under pressure, and this force being applied through the driving machinery to work a punch, as will be now more particularly described.

In Fig. 1 A is the cylinder; B¹ B² side pipes; C valve chest; D¹ D² cylinder covers; G piston rod passing through stuffing box

H, and connected to a piston in the cylinder A; I valve stem connected to a "D slide valve" placed in the valve chest C, to work over openings in the side pipes B¹ B², and 60 eduction pipe K; J induction pipe.

As all the parts referred to above by letters of reference may be of the usual mode of construction for locomotive and stationary high pressure steam engines—further 65 description of them is unnecessary.

In Fig. 1, L is a frame of a punch fastened at its upper end to the cylinder cover D², and at the lower end to the platform V, by ears W; M guide head on piston rod G, 70 70 sliding over a guide N, on the punch frame L, to guide the punch O, into the die P.

I now come to the regulating connection before mentioned. In Fig. 1 Q¹ Q² are connecting arms having their ends at X¹ X², 75 connected to the guide head M, and piston rod G, by a pin Y¹ passing through them, with nuts R¹ R² on each end of the pin Y¹, to hold them together, and forming a vibrating joint on the pin Y¹; the other end of 80 the arms Q¹ Q² are connected at X³ X⁴, by the pin Y² to a socket &, on one end of the connecting rod S, with nuts R³ R⁴, on each end of the pin Y², to hold them together, and forming a vibrating joint on the pin Y²; 85 the other end of the connecting rod S, is attached by a pin Y³, to the jaw T on the valve-stem I with nuts R⁵ R⁶ on each end of the pin Y³ to hold them together, and forming a vibrating joint on the pin Y³; U, handle for the operator, connected to the arm Q, by the pin Z, passing through it and riveting into the arm Q, so as to allow the handle U, to turn around on the pin Z; a operator standing on platform V, and grasping with 90 95 his hand the handle U.

Operation (not including the regulating connection): Example 1. Reference being had to the accompanying drawing Fig. 1, with the induction pipe J, communicating 100 the propelling force, the valve stem I, in the center of its movement, and the "D slide valve" attached closing the induction and eduction openings to the cylinder; then, by the movement of the valve stem I, and "D 105 slide valve" attached, they being the applying machinery upward, that is, in the direction from 1 to 2, so as to open a communication from the valve chest C, to the lower end of the cylinder, and from the eduction 110 pipe K, to the upper end of the cylinder, the propelling force will pass through the

side pipe B^2 , and be applied to the under side of the piston in cylinder A, causing it with the piston rod G, guide head M, and punch O, they being the driving machinery, to move upward with a force according to the amount of propelling force applied by a greater or less upward movement of the applying machinery, until the piston reaches the upper end of the cylinder.

- 5 10 Example 2. By the movement of the applying machinery downward, that is, in the direction from 2 to 1, so as to open the communication from the valve chest C, to the upper end of the cylinder A, and from the 15 eduction pipe K, to the lower end of the cylinder, the propelling force will pass through the side pipe B^1 , and be applied to the upper side of the piston in the cylinder A, causing the driving machinery to move 20 downward with a force according to the amount of propelling force applied by a greater or less downward movement of the applying machinery, until the piston reaches the lower end of the cylinder. The operation 25 as above explained by Examples 1, and 2, of the parts therein referred to being well known and understood by engineers.

I will now explain the operation of the regulating connection, combined with the 30 motion of the operator, and in connection with the operation as before explained in Examples 1, and 2, of the applying and driving machinery.

- 35 Example 3. Reference being had to the accompanying drawing Fig. 1, the operator having hold of the handle U, then by the upward motion of the operator, the handle U and pin Z will move upward; the connecting arms $Q^1 Q^2$ will turn on the pin Y^1 , their ends at $X^3 X^4$ moving up the connecting rod S, and applying machinery, and thereby causing an upward motion of the driving machinery, as before explained in example 1, with this difference, that should 40 the driving machinery start at any time while in operation to move with any other than a corresponding motion the connecting arms $Q^1 Q^2$ would vibrate on the pin Z the hand of the operator acting as a fulcrum and 45 raise or lower the applying machinery and thus increase, diminish or reverse the application of the propelling force to the piston in the cylinder A, so as thus to cause a corresponding motion of the driving machinery for 50 in the movement of the driving machinery upward the arms $Q^1 Q^2$, would turn upward on the pin Y^2 ; and should the motion of the operator, handle U, and pin Z upward be such as would be generated by the arms 55 $Q^1 Q^2$, turning upon the pin Y^2 , without moving the applying machinery, then the driving machinery would be moving with a corresponding motion, but, should the driving machinery move up faster than a corresponding motion then the arms $Q^1 Q^2$,

would not only turn up at their ends $X^1 X^2$, but would also move down at their ends $X^3 X^4$ vibrating on the pin Z, in consequence of this pin being held by the operator, and thus move the connecting rod S, and applying machinery downward so as to diminish the application of the propelling force to the piston in the cylinder A, and thus produce a corresponding motion of the driving machinery. Or should the driving 75 machinery move up slower than a corresponding motion, the action of the operator on the handle U, would draw up the ends of the arms $Q^1 Q^2$ at $X^3 X^4$, and thus raise the connecting rod S, and applying machinery, and thereby increase the application of the propelling force to the piston in the cylinder A, and thus produce a corresponding motion of the driving machinery.

80 Example 4. Reference being had to the accompanying drawing Fig. 1. The operator having hold of the handle U, then, by a downward motion of the operator, the handle U and pin Z will move downward; the connecting arms $Q^1 Q^2$ will turn on the pin Y^1 , their ends at $X^3 X^4$ moving down the connecting rod S and applying machinery, and thereby causing a downward motion of the driving machinery as before explained in Example 2, with this difference, that should the driving machinery start, at any time while in operation to move with any other than a corresponding motion the connecting arms $Q^1 Q^2$ would vibrate on the pin Z, and raise or lower the applying machinery as required by the too fast or too slow motion of the driving machinery, and thereby, increase, diminish or reverse the application of the propelling force to the piston in the cylinder A, so as 90 thus to cause a corresponding motion of the driving machinery, for in the movement of the driving machinery downward the arms $Q^1 Q^2$, would turn downward on the pin Y^2 , and should the motion of the operator, handle U and pin Z downward be such as would be generated by the arms $Q^1 Q^2$ turning upon the pin Y^2 , without moving the applying machinery, then the driving machinery would be moving with a corresponding motion, but should the driving machinery move down faster than a corresponding motion, then the arms $Q^1 Q^2$, would not only turn down at their ends $X^1 X^2$, but would 95 also move up at their ends $X^3 X^4$ vibrating on the pin Z, in consequence of this pin being held by the operator, and thus move the connecting rod and applying machinery up, so as to diminish the application of the propelling force to the piston in the cylinder A, and thus produce a corresponding motion of the driving machinery, or should the driving machinery move down slower than a corresponding motion, the action of the operator on the handle U, would draw 100

down the ends of the arms $Q^1 Q^2$, at $X^3 X^4$, and thus lower the connecting rod S , and applying machinery, and thereby increase the application of the propelling force to the piston in the cylinder A , and thus produce a corresponding motion of the driving machinery. And it is evident with reference to the accompanying drawing, and Examples 3 and 4, that the driving machinery will move only with a corresponding motion or nearly so, and that any deviation therefrom will be rectified by the movement and operation of the regulating connection, and it will also be evident reference being had to this specification and accompanying drawings generally, that the regulating connection may be variously arranged and located between different kinds of applying and driving machinery, as in Fig. 2. The driving machinery may consist of a flat bar G , guide head M and punch O . The applying machinery may consist of the crooked lever D and two rollers $A B$ which rollers are geared to power and turning in the same direction, with proper bearings for the journals F, H, I, J, K , of the lever and rollers to work upon, and the regulating connection may consist of the connecting arm Q , handle U for the operator, the connecting rod S , with the pins $Y^1 Y^2 Y^3$ to form joints, with the nuts R^1, R^2, R^3 , to hold all together. Supposing the rollers $A B$; to turn around in the direction from 1 to 2, then by the upward motion of the operator, the roller B would be pressed hard against the bar G , and the roller A be held loosely against it; the action of the friction between the roller B and bar G , would cause a corresponding motion of the driving machinery upward or by a downward motion of the operator the roller A would be brought hard against the bar G , and the roller B be held loosely against it, producing a corresponding motion of the driving machinery downward by the movement and operation of the regulating connection. The lever D could act on driving belts as on an ordinary machine for planing iron instead of the driving rollers $A B$ with the same result.

It is evident that the less labor required to work the applying machinery, the less

will be the labor of the operator. It would therefore be advisable, when the advantage justified the expense, to use that plan of applying machinery, which would require the least amount of power to work it; as in Fig. 3 the applying machinery may be operated by a rock shaft A , and this shaft be arranged to work double or balance valves, as are used in the construction of low pressure steam boat engines. And it is also evident that the less elasticity possessed by the propelling force, the more accurate will be the corresponding motion of the driving machinery, and therefore, water or other fluids will be preferable to air, steam, or any gases when great accuracy is required.

By a difference in the relative position and lengths of the connections to the operator, a difference in the direction and velocity of the corresponding motion of the driving machinery, as compared with the motion of the operator can be readily effected, as by connection to a bell-crank lever B which turns on a pin at E Fig. 3, the movement of the operator would be at right angles if connected to a handle at C , to what it would if connected to a handle at D , or would be of different velocities according to the length or lengths of the lever or levers from the applying and driving machinery to the operator. The driving machinery can operate cutters or hammers instead of a punch as here represented, or do any other work within its power to perform without affecting the principle of the operation of the regulating connection.

Having thus fully explained the nature and operation of my improvement; what I claim therein as new and desire to secure by Letters Patent is—

The use of the within described regulating connection to be acted on by an operator and applied between and in connection with applying and driving machinery so as to regulate the amount of moving power substantially on the principle and in the manner as herein described.

FREDERICK ELSWORTH SICKELS.
